UNITED STATES PATENT OFFICE.

AUGUST SCHEFFNER, JR., OF ELBERFELD, GERMANY.

DESIGN FOR A FABRIC.

SPECIFICATION forming part of Design No. 21,343, dated February 16, 1892.

Application filed January 20, 1892. Serial No. 418,704. Term of patent 3½ years.

To all whom it may concern:

Be it known that I, AUGUST SCHEFFNER, Jr., a citizen of Germany, residing at Elberfeld, Germany, have invented and produced a new and original Design for a Fabric, of which the following is a full, clear, and exact specification, reference being had to the accompanying drawing, forming a part thereof, which represents a plan view of a piece of fabric.

The principal feature of the design consists of two fanciful floral bouquet figures A and B, the other figures in the drawing being simply repeats of the main figure. The bouquet figure A consists of a grouping comprising a representation of a large rose and rosebuds of a cultivated type, surrounded here and there by smaller flowers of the wild-rose type, and in conjunction with the flowers leaves are arranged in natural and in fanciful positions,

while at one side of the bouquet figure a fan- 20
ciful scroll appears as emanating from it.

The bouquet figure B is composed of the representation of a large rose of a cultivated type, rosebuds, a large flower simulating a wild rose, smaller flowers of the pink type, and 25 leaves arranged in substantially natural positions and located adjacent to the flowers. The two bouquet figures are arranged with such relation to each other that they appear in a degree connected. 30

I claim—

A design for a fabric, substantially as herein shown and described.

AUGUST SCHEFFNER, JR.
